DESIGN FOR A HOT FUDGE WARMER

Ralph P. Olmstead, Milwaukee, Wis., assignor to
Robert A. Johnston Company, Milwaukee, Wis.,
a corporation of Wisconsin

Application October 9, 1935, Serial No. 58,901

Term of patent 3½ years

To all whom it may concern:

Be it known that I, Ralph P. Olmstead, a citizen of the United States, residing at Milwaukee, in the county of Milwaukee and State of Wisconsin, have invented a new, original, and ornamental Design for a Hot Fudge Warmer, of which the following is a specification, reference being had to the accompanying drawing, forming part thereof.

The figure is a perspective view of a hot fudge warmer, showing my new design.

The single view shown in the drawing illustrates the front of the hot fudge warmer. All portions thereof not shown are plain cylindrical surfaces.

I claim:

The ornamental design for a hot fudge warmer, as shown and described.

RALPH P. OLMSTEAD.
